(57) **CLAIM**

The ornamental design for a golf club support apparatus, as shown and described.

DESCRIPTION

FIG. 1 is a perspective view of a golf club support apparatus showing my new design;

FIG. 2 is a front elevational view thereof;

FIG. 3 is a rear elevational view thereof;

FIG. 4 is a side elevational thereof;

FIG. 5 is a top plan view thereof; and,

FIG. 6 is a bottom plan view thereof.

The broken line showing is included for the purpose of illustrating and forms no part of the claimed design.
